United States Patent Office

Des. 208,317
Patented Aug. 15, 1967

208,317

FOOD SERVICE PLATE

Leonard J. Broder, 3192 Darvany Drive,
Dallas, Tex. 75220

Filed Sept. 19, 1966, Ser. No. 3,921

Term of patent 14 years

(Cl. D44—10)

Fig. 1

Fig. 2

Fig. 3

FIG. 1 is a perspective view of a food service plate embodying my new design;

FIG. 2 is a right side elevational view thereof; and

FIG. 3 is a front elevational view thereof.

The essential features of the design are shown in full lines.

I claim:

The ornamental design for a food service plate, as shown and described.
